ANTONY GEORGES MÉKER, OF ASNIÈRES, FRANCE, ASSIGNOR TO LA SOCIÉTÉ POUR L'UTILISATION DE L'AIR ET DE SES DÉRIVÉS, OF PARIS, FRANCE.

INCANDESCENT GAS-BURNER.

No. 884,834.

Specification of Letters Patent. Patented April 14, 1908.

Application filed November 4, 1907. Serial No. 400,584.

To all whom it may concern:

Be it known that I, ANTONY GEORGES MÉKER, a citizen of the Republic of France, and resident of Asnières, France, have invented a new and useful Incandescent Gas-Burner, which burner is fully set forth in the following specification.

The present invention has for its object a burner intended either for heating or for incandescent lighting, this burner utilizing any combustible gas or vapor, coal gas, poor gases, carbureted air, hydrocarbon vapor etc. and employing oxygen or air enriched in oxygen as comburent, the action of this comburent being supplémented or not as desired by the action of atmospheric air.

The burner hereinafter described is devised with the object of utilizing oxygen of a purity of 95-97% but it will of course be understood that it may utilize pure oxygen and also oxygen of very different degrees of purity, the efficiency only differing. This form of burner, which is represented by way of example in the accompanying drawing, has been devised with the object of economizing the consumption of gas and in particular of oxygen, while at the same time avoiding the carbon deposits which form very readily in appliances of this nature.

In the accompanying drawing, in which the same reference characters denote the same parts throughout the several views, Figure 1 is a vertical section of an illuminating incandescent gas burner constructed in accordance with the invention, Fig. 2 is a detail plan view of the head of the burner, Fig. 3 is a vertical section through a controlling cock of modified form, Fig. 4 is a vertical section of a burner particularly intended for heating purposes, and Fig. 5 is a detail plan view of the head of the burner shown in Fig. 4.

Referring to the drawing, and particularly to Fig. 1, it will be seen that the burner is controlled by a double cock the casing of which is provided with two lateral gas inlets *a*, *a'*, as indicated by the dotted lines.

The inlets for the gas to the cock may be constructed differently and one only may be arranged laterally and the other on the connection which serves to fix the burner on its supports or both may be on the connection converted into a junction connection as shown in Fig. 3. The single plug *c* of the cock is provided with passages corresponding to the gas inlets, so that in the open posi-

tions the gases flow through the passages of the connections *d* and *d'*.

In order to prevent the gases from passing from one system of channels to the other as a result of leakages, the plug is provided near its middle part with a groove *e* which communicates with the atmosphere through the orifice *f*. This arrangement renders it quite impossible for a premature mixing of oxygen and gas to take place and consequently eliminates all danger of explosion. It will of course be understood that this groove may be formed upon the plug itself, the casing carrying only the discharge aperture which may be located at any part of the circumference.

By appropriately regulating the orifice for the passage of the oxygen, this gas may be caused to reach the burner first, the object of this arrangement being to avoid any trace of carbon on the incandescent mantle. The burner itself is in communication with the connection *d* and *d'* by the intermediary of the tubes *h* and *h'* and of the connections *g* and *g'*. This arrangement is given by way of example only, however, and may be replaced by any other arrangement providing a gas-tight connection between the cock and the burner itself.

Burners in which oxygen is used develop great heat with a flame of small volume; owing to this the burner is subjected to a very high temperature and after it has been burning for some time heats all parts of the system by conductivity and produces a harmful influence upon the efficiency and the operation of the device; this heating also constitutes a serious inconvenience as regards moving the device by hand. In order to avoid this transmission of the heat to all parts of the system, the tubes *h* and *h'* are formed of a metal or an alloy which is as bad a conductor of heat as possible, say German silver, steel, nickel or the like. The burner itself is constructed in such a manner as to distribute the oxygen in the form of separate jets at the base of a flame or rather of a series of jets of combustible gas. The oxygen conducted through the tube *h'* becomes distributed in the chamber *j'* of the burner-casing and thence flows through the tubes *k*, a larger or smaller number of which may be provided according to the size of the burner and the purpose for which it is to be used.

Fig. 2 shows in plan the appearance of the

head of the burner. The tubes *k* come very slightly above or on a level with the partitioned part *l*. The combustible gas conducted through the tube *h* becomes distributed in the chamber *j* which is traversed in the direction of its height by the oxygen tubes *k*. For the purpose of causing the gaseous current to be distributed uniformly at the upper part of the chamber *j*, a distributing device is provided. This preferably takes the form of a cellular part *l* which is formed by setting metal strips cut in the form of combs at 90° to each other, whereby a honeycomb partitioning is produced, the cells of which are square in section. The main object of this arrangement is to provide a part resisting the action of heat owing to the very small ratio existing between the surface of the system in contact with the flame and the total surface of the strips of this system which is likewise constantly cooled by the flow of gas; another advantageous feature of this system is the division of the gaseous column into as many separate jets as there are cells, the adjacent jets of an oxygen tube forming with these cells a burner unit and the combination of several of them under the same mantle, or on one and the same stove, constituting a single burner.

In the case of an illuminating burner the mantle *p* may be carried by a screw clamp *o* fixed to the socket *m* or to another detachable socket fitting into the former. The mantle is held in place by an ordinary suspension rod which may be an external rod as represented in the drawing or a central rod, the central hole of the cellular system being well adapted for this purpose.

The regulation of the supply of the two gases is effected by the parts *r* and *r'* which may be located at any part of the apparatus or even in front of the apparatus and in this case these parts are replaced by simple cocks. The said parts are provided with a hole of sufficient size to permit of the passage of the quantities of gas required for the efficient operation of the burner. Instead of being provided with a hole, these parts may be tapered on one side; they fit into their casing frictionally.

In cases in which the combustible and combustible gases are not supplied to the apparatus at constant or uniform pressure, and

if the pressures do not vary simultaneously, it is readily possible to interpose supply regulators between the connections *d*, *d'* and the tube *h*, *h'* which maintain the ratio between the two gases constant.

In the modification shown in Fig. 4 the tubes *h* and *h'* are also formed of a metal which is as bad a conductor of heat as possible, the oxygen is distributed by the tubes *k* above the cellular system *l*; the number of tubes and their arrangement varies in accordance with the dimensions of the burner and the purpose for which it is used; there should be a sufficient number of them and their diameters should be large enough to prevent the oxygen from escaping with an excessive velocity; the regulation of the supplies of gas is effected outside the apparatus by means of the corresponding cocks as shown diagrammatically in Fig. 4.

Having thus described my invention, I claim:

1. In an incandescent gas-burner, the combination of a casing divided into chambers arranged one above the other, means to conduct gas to one of said chambers, means to conduct oxygen to the other chamber, tubes leading upwardly through the upper chamber from the lower chamber to the top of the casing, and a plurality of strips or partitions arranged in the form of a honeycomb extending about said tubes at the upper end of the casing and forming discharge orifices for the upper chamber.

2. In an incandescent gas-burner, the combination of a casing divided into upper and lower chambers, means for supplying oxygen to the lower chamber, means for supplying gas to the upper chamber, a series of tubes leading from the lower chamber through the upper and extending above the casing, and a plurality of metal strips superposed on the casing and extending about the upper ends of said tubes, said strips being arranged to form a plurality of discharge orifices for the gas.

In testimony whereof I have signed this specification in the presence of two subscribing witnesses.

ANTONY GEORGES MÉKER.
